CROWN CAP SELECTING MACHINE

Louis A. Fischer, Brooklyn, N. Y., assignor to The
F. & M. Schaefer Brewing Company, Brooklyn,
N. Y., a corporation of New York

Application September 4, 1943, Serial No. 501,327

3 Claims. (Cl. 226—88.1)

This invention relates to crown cap selecting machines, and has for its object to provide means for inspecting the interior of such machines while the same are running, and also provide means for preventing the caps from clogging during the operation of the machine.

In the use of such cap selecting machines, it frequently happens that inspection of the interior of the same becomes necessary and also that certain caps which have become clogged be removed. Also certain foreign matters must be dislodged.

This requires a shutting down of the machine and a re-starting, this requiring several hours of non-use of the machine.

The invention consists of a door closed opening which permits the caps to be ejected from the machine, capable of being opened and closed during the operation of the machine, and the invention also consists in the means for preventing clogging of caps.

The invention will be more fully described hereinafter in connection with the embodiments shown in the drawings, and will be finally pointed out in the claims.

In the accompanying drawings,

Figure 1 is a partial front view of a selecting machine with my improvements applied thereto.

Figure 2 is a vertical section of Figure 1 taken on line 2—2 of Figure 1.

Figure 3 is a section on line 3—3 of Figure 1.

Figure 4 is an enlarged sectional view of the door parts of Figure 2.

Figure 5 is a section on line 5—5 of Figure 4, and

Figure 6 is a view taken on line 6—6 of Figure 4, looking in the direction of the arrows.

Similar characters of reference indicate corresponding parts throughout the various views.

Referring to the drawings, and more particularly to Figures 1 and 2, a front view and section of a known selecting machine are there shown.

The shaft 10 rotates casing 13 and in turn rotates disc 11, by means of screws spaced in studs 12. The casing 13 receives the crown caps, such as 14, and these from their tumbling position arrange themselves between the studs 12 and when the caps arrive in a position above the guideway 15, they descend therein in an aligned manner. These parts and operations are well known.

Sometimes the caps become clogged and to avoid superposing of caps or clogging, the improvement consists in providing a blade spring 20 secured at its end 21 to the hopper 16, and depending to prevent the entrance of caps into a

rounded toothed wheel 23 pivoted at 24 and having its rounded teeth 25 enter between two adjacent studs 12. The disc 11 rotates in the direction of the arrow 26 and the toothed wheel 22 in the direction of the arrow 27.

A double bent spring 28 is secured at 28a to the hopper 16 to prevent the caps from spacing between the studs.

And if any caps are clogged, the toothed wheel 10 removes the same.

The other improvement consists in providing a door, which may be opened or closed while the machine is running, the door rotating and caps being discharged through the door opening with each revolution.

Should any caps cause trouble in the operation, which frequently happens, a door 30 is opened and the caps can drop out and thereafter any clogged cap or other material causing an obstruction can be removed during the rotation of the shaft 10.

The door 30 is hinged at 31 to the outer cover 32, a spring 33 being provided. The door is fixed to an arm 34 having one end extended at 34a beyond the door 30, to seat against the casing 13. The extension 34a acts as a stop. To the other end of the arm 34 there is affixed a shaft 35 fixed in an opening of the arm. The shaft at its other end 36 is secured to a disc 37 which has a groove

38 therein, to receive seven balls 39 as shown. This number of balls is preferred, but any suitable number can be used. This is surrounded by a cover 40 with an enclosing flange 42 bent in but slightly spaced from the disc 37. When the

shaft 35 contacts with the end of the shaft 10, the arm 34 and the shaft 35 is rotated, whereupon the grooved disc 37 rotates, but the cover 40 is held in the hand, and pressed by the hand with shaft against shaft, when the door 30 is open. When it is desired to close the door 30 the cover 40 and enclosed grooved disc and shaft is removed from the shaft 10 and lowered, and the door closes and remains closed until the above operation is repeated.

It will have been noted that the teeth of the toothed wheel mesh into crown passageways of the crown hopper, forcing any obstruction back into the feed chamber bin. The flat spring 20 arrangement is used ahead of the toothed wheel to hold the crowns away from the gear mechanism.

The hinged door 30 in the outside face of the feed chamber bin is held normally closed by the spring 33. The door 30 is opened by moving the arm fastened to the door to a position where the center of the shaft, on which the handle

turns is in line with the center of the rotating feed chamber bin. This allows the operator to hold the door in open position while the door and arm rotate around the shaft in the handle.

I have described the improvements in connection with the embodiments shown, but changes can be made therein without departing from the spirit of the invention as defined in the appended claims.

What I claim is:

1. In a crown cap selecting machine, a rotatable shaft, a casing front having a cap discharging opening rotating with said shaft, a door in said casing front for closing and opening said opening, means holding said door normally in closed position, means for holding said door open during the rotation of the casing front, said last named means rotating with the casing front, and having means when aligned with the shaft to be held against rotation, during the rotation of said shaft, said holding means and said casing front.
2. In a crown cap selecting machine, a rotatable shaft, a casing front rotating with said shaft and having an opening for the discharge of caps, a door on said casing front closing said opening, 25

said door being hinged to said casing front and rotating therewith, and an operating arm connected at one of its ends to said door and rotating therewith and extending to the axis of the shaft when the door is open, and means on the last named end of said arm to contact with the shaft when the door is open.

3. In a crown cap selecting machine, a rotatable shaft, a casing front rotating with said shaft and having an opening for the discharge of caps, a door on said casing front closing said opening, said door rotating with the casing front, an operating arm having one end connected with said door, a shaft at the other end of said arm 10 adapted to contact with the first named shaft, a disc having a groove therein supported by said second shaft, balls in said groove, and a closure extending over said second shaft, said closure contacting with said balls and extending over said disc, whereby when the second shaft contacts with the first shaft the door is open and rotates with the casing and said closure when held by the hand preventing its rotation during the rotation of the operating arm.

LOUIS A. FISCHER.
